REFRIGERATOR

Homer E. Rosebrock, Greenville, Mich., assignor,
by mesne assignments, to Gibson Refrigerator
Company, Greenville, Mich., a corporation of
Michigan

Application June 12, 1941, Serial No. 397,680

7 Claims. (Cl. 62—89)

1

This invention relates to refrigerators, and more particularly to the provision of auxiliary compartments within such refrigerators for the storage of butter and other foodstuffs which it is desired to maintain at a temperature higher than that of the remainder of the articles stored within the refrigerator.

The temperature normally maintained within the main food storage compartment of a refrigerator is so low that butter kept at that temperature will not spread easily. Butter and similar foodstuffs, however, can be properly preserved at temperatures somewhat higher than those prevailing in the main compartment. Hence, it is desirable to provide in the refrigerator cabinet an auxiliary compartment which can be kept at a higher temperature than that of the main compartment, yet sufficiently low to preserve butter and the like.

Accordingly, the principal object of this invention is to provide in a refrigerator an auxiliary insulated compartment for the storage of butter and similar foodstuffs.

A further object is to provide novel means for conducting heat to the auxiliary compartment whereby to maintain it at a temperature higher than that of the main compartment.

Another object of the invention is to improve the efficiency of the refrigeration system of refrigerators provided with such auxiliary compartments.

Another object is to provide a combined heat transfer means and support for an auxiliary compartment.

These and other objects ancillary thereto will more fully appear in the following specification, when read in connection with the accompanying drawings, wherein:

Figure 1 is a front elevational view of a refrigerator of the household type embodying the invention, the door of the refrigerator being open to show the interior thereof;

Figure 2 is a fragmentary front elevational view on an enlarged scale of the auxiliary compartment;

Figure 3 is a fragmentary cross-sectional view taken on substantially the line 3—3 of Figure 2;

Figure 4 is a fragmentary cross-sectional view taken on substantially the line 4—4 of Figure 2;

Figure 5 is a fragmentary front elevational view of a modified form of the invention;

Figure 6 is a fragmentary cross-sectional view taken on substantially the line 6—6 of Figure 5; and

2

Figure 7 is a fragmentary cross-sectional view taken on substantially the line 7—7 of Figure 5.

The invention is shown as embodied in a conventional household refrigerator, shown in Figure 1. The refrigerator comprises a cabinet having an outer casing 10. Within the outer casing 10 and spaced therefrom is a liner 11 defining a main refrigerated food storage compartment. Insulation 24 is packed between the liner 11 and the outer casing 10. The main compartment is provided with a door 12. Within the main compartment is an evaporator 13 for cooling the main compartment. Shelves 14 are provided for holding articles to be stored within the refrigerator.

In the bottom of the refrigerator cabinet is a machinery compartment having an access door 15. The machinery compartment contains a part of the refrigeration apparatus which may be of any conventional type. A condenser 17, which is connected to, and forms a part of the refrigerating system, is mounted in an upright position in the rear of the back wall of the cabinet. The condenser may comprise a continuous coil of tubing, such as that shown. A flue 16, open at its upper and lower ends, encloses the condenser 17 and is secured to the back of the cabinet 10.

Located within the main compartment is a housing 18 forming an auxiliary compartment. The housing 18 comprises a shell 19 having an access opening therein which is closed by closure 20. The closure 20 is hinged to the shell 19 by hinges 21 positioned adjacent to the lower edge thereof. Both the shell and the closure are preferably formed from a suitable plastic material which is to a certain extent an insulating material. That is, the plastic material has a coefficient of heat transfer lower than those of the various metals, but higher than those materials which are commonly called insulating materials. Thus, when the temperature within the auxiliary compartment is higher than that within the main compartment, there will be a relatively slow transfer of heat from the auxiliary compartment to the main compartment through the walls surrounding the former.

The shell 19 of the auxiliary compartment is mounted on the back wall of the liner 11 by means of a U-shaped metal bar 22. The base of the U is located outside of the outer wall of the cabinet and is preferably in direct contact with a portion of the condenser 17. The legs of the U extend through the back walls of the casing 10 and the liner 11 and into housing 18. The legs of the U are secured to the side walls of the shell 19 by screws 23. In order to prevent direct

contact and consequent conduction of heat from the bar 22 to the liner 11, rubber grommets 25 are interposed between them. The grommets also seal the holes in the liner through which the bar 22 passes, thereby preventing the escape of moisture into the insulation 24.

The auxiliary compartment is cooled by the evaporator 13. The auxiliary compartment cannot become as cold as the main compartment because it is constantly being warmed by heat from outside the cabinet conducted through the bar 22. The air within the auxiliary compartment will absorb this heat and thereby maintain the temperature of the auxiliary compartment above that of the main compartment.

Since the arrangement just described conducts heat from the exterior of the refrigerator into the interior thereof, it would be expected to cause a slight decrease in the efficiency of the refrigerator. This loss, however, will be offset to a considerable extent by absorbing the heat from the condenser 17. Since the condenser 17 has to be cooled and the bar 22 is to be heated, arranging them in heat exchange relation increases the efficiency of the condenser. This arrangement is much superior to an arrangement wherein the heat transfer means is exposed only to the air outside the refrigerator because the heat loss in that case is an absolute waste.

Figures 5 to 7 show a somewhat modified form of the invention. The housing which forms the auxiliary compartment in this modification is designated by the reference numeral 50. The refrigerator in which the housing 50 is mounted may be the same as that previously described. It comprises an outer casing 10' and a liner 11' with insulation 24' between them. At the back of the refrigerator is a condenser 17' partially surrounded by a flue 16'.

The housing 50 comprises an outer shell 51 and a hinged closure 52. Preferably the shell and closure are made from a plastic the same as that in the previously described construction. The shell 51 of the housing 50 is secured in any suitable manner, preferably by screws 53, to the back wall of the liner 11' of the refrigerator cabinet.

In this modification of the invention the heat transfer means is a closed refrigerant circuit. It comprises a continuous coil of hollow tubing 55 which is looped back and forth within the shell 51 and extends through the back walls of the liner 11' and the casing 10' of the refrigerator cabinet. The portion outside of the cabinet is bent into the shape shown in Figures 5 to 7, and is arranged so that a portion thereof is in contact with the condenser 17'.

The tubular refrigerant circuit 55 is partially filled with a suitable volatile refrigerant. The quantity of refrigerant employed within the coil is such that at the temperatures prevailing within the auxiliary compartment a portion of the refrigerant is liquified. Liquid refrigerant collects in the bottom part of the coil and in the lowermost loop of the coil outside of the refrigerator. Here it absorbs heat from the condenser 17' and is evaporated. The gaseous refrigerant then passes back into the auxiliary compartment where it gives up its heat and is again liquified. Thus it will be seen that the refrigerant circuit 55 is in effect a closed system wherein the evaporator is that portion outside the refrigerator and in contact with the condenser 56 and wherein the condenser of circuit 55 is that portion within the auxiliary compartment.

In this modification, as in the previously de-

scribed construction, a portion of the heat from the condenser 17' is utilized to evaporate the liquid refrigerant in the coil 55, hence there is no appreciable loss in efficiency of the entire refrigerator.

From the foregoing it will be seen that the invention provides an auxiliary compartment which can be maintained at temperatures above those within the main food storage compartment whereby butter and other foodstuffs can be properly preserved, without causing an appreciable loss in the efficiency of the refrigerator as a whole.

Furthermore, in the modification shown in Figures 1 to 4 the U-shaped bar which forms the heat transfer medium, also provides the sole support for the auxiliary compartment.

The scope of the invention is indicated in the appended claims.

I claim:

1. A refrigerator including, in combination, a cabinet formed to provide a main refrigerated compartment, a housing in said main compartment defining an auxiliary compartment, the walls of said housing being formed of relatively poor heat conducting material, means for refrigerating said main compartment including a condenser located outside of said main compartment, and heat transfer means for maintaining the temperature within said auxiliary compartment above that within the main compartment, said heat transfer means having a portion in heat exchange relation with said condenser and another portion in heat exchange relation with said auxiliary compartment, said last named portion being substantially insulated from said main refrigerated compartment.

2. A refrigerator as defined in claim 1 wherein said heat transfer means comprises a closed refrigerant circuit containing a volatile refrigerant.

3. A refrigerator comprising, in combination, a cabinet formed to provide a main refrigerated compartment, a housing in said main compartment defining an auxiliary compartment, the walls of said housing being formed of relatively poor heat conducting material, and heat transfer means for maintaining the temperature within said auxiliary compartment above that within the main compartment, said heat transfer means comprising a closed refrigerant circuit having a condenser portion in heat exchange relation with said auxiliary compartment and an evaporator portion located outside of the cabinet and in heat exchange relation to the air outside of the cabinet, said condenser portion being substantially insulated from said main refrigerated compartment.

4. A refrigerator comprising, in combination, a cabinet formed to provide a main refrigerated compartment, a housing in said main compartment defining an auxiliary compartment, heat transfer means for transferring heat to the air within the auxiliary compartment to maintain it at a temperature above that within the main compartment, said heat transfer means comprising a closed refrigerating circuit containing a volatile refrigerant and having a condenser portion within said auxiliary compartment and the evaporator portion outside of said refrigerated compartment, said condenser portion being substantially insulated from said main refrigerated compartment.

5. A refrigerator as defined in claim 4 wherein said closed refrigerating circuit comprises a continuous tube containing a volatile refrigerant.

6. In a refrigerator cabinet having a refrig-

erated compartment and a food storage receptacle within said compartment, means including a hermetically sealed container partially filled with a vaporizable liquid for transferring heat from a suitable source thereof to the interior of said receptacle.

7. In a refrigerator cabinet having a food storage compartment, a refrigerant circulating sys-

tem for providing refrigeration in said compartment, and a food storage receptacle within said refrigerated compartment, means including a hermetically sealed container partially filled with a vaporizable liquid for transferring heat from a portion of said system to the interior of said receptacle.

HOMER E. ROSEBROOK.
